UNITED STATES PATENT OFFICE

BENJAMIN HARRISON FLYNN, OF AMARILLO, TEXAS

TURNING EQUIPMENT FOR HEAVY MACHINES

Application filed February 5, 1930. Serial No. 426,075.

When using large and cumbersome mobile machines, for instance, graders and other equipment for highway construction, it is often necessary or desirable to swing a machine to an out-of-the-way position at one side of its course, allowing vehicles, other equipment, etc. to pass. Heretofore, such operations have required the services of a great number of men and have been long and arduous, often necessitating that the machine be jacked up and its transportation wheels or treads applied before it can be swung. It is an object of my invention however, to provide new and advantageous means allowing the machine to be quickly and easily swung from its course whenever desired and returned to such course with equal speed and ease.

With the foregoing in view, the invention resides in the novel subject matter herein-after described and claimed, description being accomplished by reference to the accompanying drawing.

Fig. 1 is a top plan view showing a power driven road grader in its normal position upon a supporting track and swung to one side in dotted lines.

Fig. 2 is an enlarged vertical section partly in elevation illustrating the combined jack and vertical pivot with which the machine is provided.

Fig. 3 is a perspective view showing one manner of connecting the curved switch rail with one rail of the machine supporting track.

Fig. 4 is a fragmentary perspective view illustrating the manner in which the switch rail crosses the other track rail.

In the drawing above briefly described, the numerals 5 and 6 denote two rails upon which a heavy machine 7 is supported, and in the present showing, the rails may be considered as side forms used in highway construction, and the machine 7 considered as a power-operated grader. While the general construction of the machine 7 does not enter into the present application, it may be explained that the numerals 8 denote front and rear axles having flanged wheels 9 resting upon the rails 5 and 6, said axles being driven by

a motor 10 and appropriate driving connections, to drive all four of the wheels 9. The machine 7, it will be observed, is of greater dimension transversely of the track 5-6 than longitudinally thereof. Hence, if it be swung to a longitudinal position over one of the track rails as seen in dotted lines in Fig. 1, it will allow trucks, other equipment, etc. to pass. My invention provides a novel and advantageous way for allowing such swinging of the machine.

Provision is made for elevating one end of the machine 7 from one of the track rails, leaving said end free to turn or swing about a vertical axis, said means preferably consisting of a combined jack and pivot which is denoted in a general way by the number 11.

A curved switch rail 12 is provided to engage the other track rail and occupy a position concentric with the pivotal axis about which the machine may swing. Hence, by operating the combined jack and pivot 11, or any equivalent means which may be provided, to raise one end of the machine and then driving the wheels 9 at the other end thereof, these wheels are caused to travel along the switch rail 12, causing the machine to swing about a vertical axis to an out-of-the-way position.

Due to the relation between the axis about which the machine swings, and the wheels 9 at the opposite end of the machine, it may be necessary that a portion of the rail 5 or perhaps both rails 5-6, shall spring outwardly to some extent before the rearmost wheel 9 can reach a position at which it may travel onto the switch rail 12. However, such springing will not be necessary if there be sufficient play between the wheel flanges and the track rails.

While in actual construction, a hydraulic jack is preferably used, in providing for lifting one end of the machine and establishing a pivot therefor, I have shown a conventional jack screw 13 threaded through a bearing 14 on a side bar of the machine 7, the lower end of said screw being provided with a swiveled foot 15. This foot may rest upon the track rail 6 but preferably a bearing plate 16 is laid upon this track rail, upon a portion of the ground at the outer side of said rail, and is anchored by an appropriate stake 17.

- The curved switch rail 12 is formed of separably connected sections as illustrated in Fig. 1 and all of these sections except the one finally supporting the turned machine, may be removed after the machine-turning operation, leaving the greater portion of the grade between the rails 5 and 6 unobstructed for passage of vehicles, other equipment, etc. At the end of the switch rail 12 to engage the track rail 5, the former is of course thinned horizontally in much the same manner as a conventional switch tongue, and said end is provided with any desired hook 18 to engage the rail 5 and effectively connect the switch rail therewith. At its other end, the switch rail 12 preferably crosses the track rail 6 and is formed with a notch 19 receiving said rail 6. The switch rail may extend outwardly any desired distance from the track rail 6 but in some instances it may in fact terminate at or near the inner side of said rail 6, instead of extending beyond the latter. When rail 12 crosses rail 6 as herein illustrated, the surface of rail 12 will be sufficiently above the surface of rail 6 to prevent the wheel flanges from striking upon the latter. Unless the rail 12 be gradually increased in height toward its outer end, to provide for effective bearing upon the grade between the rails 5 and 6, suitable blocks 20 may be inserted under said rail 12 to properly support the same. The combined jack and pivot 11 is a permanent part of the machine 7 and hence is always in readiness for use, and the curved switch rail 12 and any equipment which may be necessary in properly assembling and positioning it, may be carried directly on the machine. Thus, at any time, the switch rail 12 may be positioned, one end of the machine jacked up on the combined jack and pivot 11, and the other end of said machine propelled along the switch rail, thereby swinging it to a position longitudinally of the grade instead of transversely thereof. Then, removal of portions of the switch rail 12 which are not supporting the machine, permits unobstructed passage of vehicles, machines, equipment, etc., along the grade. Within the scope of the invention as claimed, numerous variations may be made with regard to materials, details of construction, etc., and it is therefore to be understood that the present disclosure is for illustrative purposes only. Attention may further be invited to the novel method of swinging the machine and it will be seen that this method may be carried out with any adequate equipment.
- I claim:—
1. In a means for swinging a mobile machine from a selected course, means for elevating one side of the machine from the supporting surface and leaving said side free to turn about a vertical axis, whereby propelling

the other side of the machine will cause it to swing from its course.

2. In a means for swinging a mobile machine from a selected course, a combined jack and vertical pivot for elevating one side of the machine above the supporting surface, whereby propelling the other side of said machine will cause the latter to swing horizontally about said combined jack and pivot.

3. In a means for swinging a track-supported mobile machine from a rail of its track, means for elevating the machine from one rail of the track and leaving said end free to turn about a vertical axis, and a curved switch rail engageable with the other rail of the track, whereby propelling one side of the machine along said curved switch rail will cause swinging of the entire machine about a vertical axis.

4. A structure as specified in claim 3; said curved rail being of a length to extend across the first mentioned track rail and having a notch to receive the latter.

5. In a means for swinging a track-supported mobile machine from a rail of its track, a combined jack and vertical pivot for elevating the machine from one rail of the track, and a curved switch rail engageable with the other rail of the track, whereby one side of the machine may be propelled along said curved switch rail and the entire machine will swing about said combined jack and pivot.

6. In a method of swinging a heavy mobile machine from its course, the steps of elevating one side of the machine and supporting it for swinging about a vertical axis, and propelling the other side of the machine to cause the latter to swing about said axis.

7. In a method of swinging a heavy mobile track-supporting machine from its track, the steps of elevating one side of the machine from one track rail and supporting it for swinging about a vertical axis, laying a curved switch rail from the other track rail to said one rail, and propelling the machine along said switch rail, causing said machine to swing about said vertical axis.

In testimony whereof I have hereunto affixed my signature.
